UNITED STATES PATENT OFFICE.

CHARLES T. YOUNG, OF HILLSBORO, OREGON.

COMBINED RULER AND BLOTTER.

1,058,652.

Specification of Letters Patent.

Patented Apr. 8, 1913.

Application filed August 21, 1912. Serial No. 716,310.

To all whom it may concern:

Be it known that I, CHARLES T. YOUNG, a citizen of the United States, and a resident of Hillsboro, county of Washington, and 5 State of Oregon, have invented a new and useful Improvement in Combined Rulers and Blotters, of which the following is a specification.

My invention relates to combined rulers 10 and blotters.

My main object is to provide a device which will be of convenience to clerks or anyone engaged in work requiring the drawing of straight lines in ink.

15 Another principal feature of my invention is the providing of a ruler adapted for having a blotter readily attached to it, and at the same time leaving the ruler perfectly flexible.

20 I attain my object and incidental features by the device illustrated in the drawing, in which—

Figure 1 is a perspective view of my device; Fig. 2 is a plan view of the flexible strip which serves as a binder between the blotter and the ruler; Fig. 3 is an end elevation, on a larger scale, without the blotter and binding strap previously referred to; Fig. 4 is a perspective view of a portion of 25 the blotter showing the form to which the latter is to be folded before it can be attached to the ruler; and Fig. 5 is a vertical, transverse section of the device taken approximately on the line 5—5 of Fig. 1, and 30 looking in the direction indicated by the arrow.

In the drawings, the ruler consists of two parallel straight-edge members *a* and *a'*, each having its outside edge graduated so 40 that such edges may be used in the same manner as the edges of an ordinary ruler. The straight-edge members *a* and *a'* are connected by a plurality of bow shaped arms *b*, *b'*, and *b''*, which rigidly hold said 45 straight-edge members slightly spaced apart from each other, as more clearly shown in Fig. 3. The blotter *d* is folded to the form shown in Fig. 4, after which the portions *d'*, *d''* are inserted in the space between the two 50 straight-edge members *a*, *a'*, the portions *d''*, *d'''* will lie under the connecting arms *b*, *b'*, *b''*, and the portion *d''* will cover the bottom surfaces of the ruler, which features are more clearly shown in Fig. 5.

55 The flexible strip, *c*, made with narrower ends *c'* and *c''*, and a wider section *c''* having

a length equal to the distance between the arms *b'* and *b''*, is inserted under the bow arms. This latter is done in the following manner: The end *c'* of the strip is slipped 60 under the arm *b'* and the arms *b*, till the shoulders *c''* of said strip abut against the sides of the arm *b'*. The enlarged section *c''* is then bent up till the end *c''* can be inserted under the arm *b''*. The resiliency of the 65 strip will then force the shoulders *c''* against the sides of the arm *b''*.

The elastic qualities of the material composing the ruler and the strip *c* are such that the device may be bent readily in either 70 direction so as to conform with the curved surface of a book, without displacing any of the parts which go to make up the device. In the bending of the ruler over a curved surface of a book the ruler and blotter, as 75 apparent, would have some relative independent movement which permits the use of my device over a curved surface; and the parts will of course resume their normal relative positions when used upon a straight 80 surface.

I claim:

1. A combined ruler and blotter, comprising two parallel straight-edge members, longitudinally flexible; a longitudinally 85 folded blotter sheet means for securing the blotter on the ruler, said means adapted to permit the blotter to have relative longitudinal movement on the straight-edge members, so as to accommodate the longitudinal 90 bending of the latter.

2. A combined ruler and blotter, comprising two parallel straight-edge members, longitudinally flexible; bow-arms connecting said members spaced apart; a longitudinally 95 folded blotter sheet having portions inserted under said bow-arms; a strip of resilient material removably inserted under the bow-arms over the blotter portions lying under the bow-arms; and means for preventing the longitudinal displacement of 100 said strip.

3. A combined ruler and blotter, comprising two parallel straight-edge members, longitudinally flexible; bow-arms connecting said members spaced apart; a longitudinally 105 folded blotter sheet having portions inserted under said bow-arms; a strip of resilient material removably inserted under the bow-arms over the blotter portions lying under the bow-arms; said strip formed with shoulders adapted for engagement with said

bow-arms, thereby preventing the longitudinal displacement of said strip.

4. A combined ruler and blotter, comprising two parallel straight-edge members, longitudinally flexible; bow-arms connecting said members spaced apart; a longitudinally folded blotter sheet having portions inserted under said bow-arms; a strip of resilient material removably inserted under the bow-arms over the blotter portions lying under the bow-arms.

5. A combined ruler and blotter, comprising two parallel straight-edge members, longitudinally flexible; bow-arms connect-

ing said members spaced apart; a longitudinally folded blotter sheet inserted between said straight-edge members, having portions lying under said bow-arms, and a portion covering the bottom face of the ruler; a strip of resilient material removably inserted under the bow-arms over the blotter portions lying under the bow-arms; whereby said blotter sheet is removably secured in place.

CHARLES T. YOUNG.
